Inventor:

Charles J. Nash

By Julian, Mann & Co., Atty's

UNITED STATES PATENT OFFICE.

CHARLES J. NASH, OF CHICAGO, ILLINOIS, ASSIGNOR TO UNIVERSAL DRAFT GEAR ATTACHMENT CO., A CORPORATION OF ILLINOIS.

RAILWAY BRAKE.

Application filed April 9, 1927. Serial No. 182,331.

This invention relates to brakes for railway cars, and more particularly to the brake operating mechanism.

One of the objects of the invention is the provision of new and improved brake operating mechanism that may be assembled with a minimum of time and labor and when assembled is efficiently held in operative position.

10 Another object of the invention is the provision of new and improved means for holding the upper and lower bearings for the winding drum in perfect alinement.

15 A further object of the invention is the provision of a brake operating mechanism that is cheap to manufacture, easily assembled, composed of few moving parts, efficient in operation, and that is not likely to become broken or get out of order.

20 Other and further objects and advantages of the invention will appear from the following description taken in connection with the accompanying drawings, in which

25 Fig. 1 is an end elevation of a portion of a railway car showing the invention in position therein; and

Fig. 2 is a section on line 2—2 of Fig. 1.

On the drawings, the reference character 10 designates a car end, or more specifically 30 the end sill of a railway car on which the brake operating mechanism is mounted.

In the construction of operating mechanism for railway brakes, it is desirable that bolts, nuts, cotter pins and the like for holding the mechanism in assembled relation be eliminated as far as possible because they are a continual source of trouble and annoyance, inasmuch as they are constantly breaking or becoming loose, or getting lost.

40 In the present invention these disadvantages are overcome by an arrangement in which the brake operating mechanism is so constructed that it is assembled without the use of bolts, nuts, keys or pins. In the form 45 of the device selected to illustrate one embodiment of the invention a unitary bracket 11 comprising a body portion 12 having a laterally extending flange 13 and a depending portion 14 is employed. The depending portion 14 extends downwardly and outwardly 50 from the body portion 12. The depending portion 14 is preferably in the form of a stirrup having a bearing 16 in its horizontal portion 17. The depending portion 14 may, if

desired, be provided with a reinforcing flange 55 18 for strengthening said portion.

The body portion 12 is provided with a laterally extending flange or ledge portion 19 which is provided with an enlarged bearing 21 in axial alinement with the bearing 16. 60

A suitable rotatable or brake operating member which, for convenience of description, will be termed a sleeve 22, which may, if desired, be provided with a conventional conical winding drum 23, to which the brake 65 chain 20 is attached, is journaled in said bearings 16 and 21. The lower end of the sleeve 22 is provided with a journal 24 for engaging the bearing 16 and the upper end of the sleeve is enlarged as at 25 to form a journal 70 for the enlarged bearing 21.

A ratchet wheel 26 provided with ratchet teeth 27 on its under side and having a hub 28 for engaging the upper end of the sleeve 22 is provided for holding the brake in applied position. A pawl 33 pivoted to 75 standing ears 34 on the ledge or flange 19 is provided for engaging the teeth 27 for holding the ratchet wheel in adjusted position. The pawl is held in or out of engagement 80 with the ratchet teeth by the pivoted weight 35 in a manner well known in the art.

The sleeve 22 and ratchet wheel 26 are provided with aligned angular openings through which the angular staff 29 extends. The staff 85 29 may, if desired, be slidably mounted in the axial openings in the sleeve and ratchet wheel and is adapted to be held in position by a slideable latch 31 having a ledge 32 for engaging beneath the staff when the same is 90 elevated. The latch is provided with a projection or handle 35 for manually moving the same upwardly out of the path of the staff when it is desired to lower the staff and brake wheel. The latch and cooperating mechanism is disclosed and claimed in application 95 of Charles J. Nash and Jack Wilson, Serial No. 74,466, filed December 10, 1925, and it is not thought necessary to further describe the same.

The ratchet wheel 26 is held in lowered position by an overhanging or retainer member 36 which may be and preferably is integral with the bracket 11. The retaining member 36 prevents the ratchet wheel 26 from rising, 105 which in turn holds the sleeve 22 in lowered position with the journal 24 in the bearing 16.

In assembling the device, the upper end of

the sleeve 22 is inserted through the bearing 21 and then lowered with the journal 24 in the bearing 16, after which the ratchet wheel is placed on top of the upper end of the sleeve 22 beneath the retaining member 36 and with its axial opening in alignment with the axial opening in the sleeve 22. The parts are then fastened in assembled relation by inserting the angular brake staff 29 through said aligned 10 openings.

The bracket is attached in any suitable manner to the end of the car, as by means of rivets 37 and 38 which secure the bracket to the end sill 10.

15 It will thus be seen that the parts may be assembled with a minimum amount of time and labor, and when assembled the construction is rigid, the bearings perfectly aligned and the elements held in assembled relation 20 without the use of bolts, screws or pins.

The brake staff 29 may be secured to the sleeve 22 in any suitable manner, this feature being immaterial so far as the present invention is concerned. It is shown as being 25 ably mounted in the sleeve, but it may be other.

While I have shown the bracket 11 as being a unitary structure, it is understood it may be otherwise, so long as the bearings 16 and 21 30 are held in vertical alignment. It is desirable that these bearings be held in vertical alignment in order that there shall be no binding of the journals on the winding mechanism during the operation of applying the brakes.

35 It is thought from the foregoing taken in connection with the accompanying drawings, that the construction and operation of my device will be apparent to those skilled in the art, and that various changes in size, 40 shape, proportion and details of construction may be made without departing from the spirit and scope of the appended claims.

I claim as my invention:

1. In a brake mechanism, a casting having 45 a pair of aligned openings therein for forming bearings, a sleeve having a winding drum rigidly secured thereon, a reduced portion on said sleeve for forming a journal for engaging the lower bearing, an angular brake shaft 50 slidably engaging said sleeve, a ratchet having an axial opening for receiving said shaft, and a stop for preventing the vertical movement of said ratchet and sleeve when the parts are assembled.

55 2. In a brake mechanism for railway cars, an upper and a lower bearing, a sleeve having a reduced portion at its lower end for engaging said lower bearing, said upper bearing of sufficient size to permit said sleeve to slide 60 therein, an angular staff slidable in a corresponding axial opening in said sleeve, a ratchet wheel engaging the upper end of said sleeve for preventing vertical movement thereof, and means for preventing vertical 65 movement of said ratchet.

3. In a brake operating mechanism for railway cars, an upper bearing, a lower bearing, means for rigidly holding said bearings in alignment, a rotatable member having upper and lower journals for engaging said 70 bearings, said lower journal being provided with a shoulder for limiting its downward movement through said lower bearing, the diameter of the upper portion of said member being less than the internal diameter of said upper bearing, whereby said member may be placed in position by inserting the upper end thereof through said upper bearing and then lowering the lower journal into said lower bearing, and means for rotating said member. 75

4. In a railway brake operating mechanism, a pair of aligned bearings, means for supporting said bearings in spaced relation on a railway car, a rotating member having a pair of journals thereon for engaging said 85 bearings respectively, one of said journals being slidable through the corresponding bearing for permitting the insertion of the other journal in its bearing, and means for preventing the disengagement of said journals and bearings when the same are assembled. 90

5. In a railway brake operating mechanism, a pair of aligned bearings, means for supporting said bearings in spaced relation 95 on a railway car, a rotating member having a pair of journals thereon for engaging said bearings respectively, one of said journals being slidable through the corresponding bearing for permitting the insertion of the other journal in its bearing, a ratchet wheel in engagement with said rotating member, a staff engaging said wheel and rotating member, and a retaining member for limiting the separation of said wheel and rotating member. 100

6. In a brake operating mechanism, a bracket, means for attaching said bracket to a railway car, a laterally extending ledge on said bracket, a retainer member extending laterally over said ledge in spaced relation thereto, said bracket terminating in a downwardly and laterally extending stirrup, and aligned bearings in said ledge and stirrup. 110

7. In a railway brake operating mechanism, a bracket having a laterally extending ledge member, a downwardly and laterally extending stirrup member on said bracket, aligned bearings in said ledge and stirrup members, a rotating member having journals for engaging said bearings, the bearing in said ledge member being of sufficient diameter to permit the rotating member to be slid therethrough for the insertion of the other journal in the bearing in the stirrup member, a ratchet element on said rotating member, an operating staff for simultaneously turning said rotating member and ratchet element, a retaining member on said bracket for preventing the disengagement of said 120 125 130

journals and bearings, and a pawl pivotally mounted on said ledge for engaging said ratchet.

8. In a brake operating mechanism, an upper bearing, a lower bearing, a rotating member having an upper journal for engaging said upper bearing and a lower journal for engaging said lower bearing, a winding member on said rotating member adjacent to the lower end thereof, the internal diameter of said upper bearing being less than the diameter of said winding member but greater than

the diameter of the upper portion of said rotating member, whereby said last named member may be placed in position by inserting said upper journal through the upper bearing, moving said rotating member into axial alignment with the axis of said bearings, and lowering said journals into said bearings, and a staff for operating said rotating member.

In testimony whereof I affix my signature.

CHARLES J. NASH.
